UNITED STATES PATENT OFFICE.

WALTER S. LEVIN, OF SAN FRANCISCO, CALIFORNIA, ASSIGNOR TO THE NATIONAL SAFETY APPLIANCE COMPANY, OF SAN FRANCISCO, CALIFORNIA, A CORPORATION OF CALIFORNIA.

AUTOMATIC BLOCK-SIGNAL SYSTEM.

1,305,382.

Specification of Letters Patent.

Patented June 3, 1919.

Application filed June 30, 1915. Serial No. 37,142.

To all whom it may concern:

Be it known that I, WALTER S. LEVIN, a citizen of the United States, and a resident of San Francisco, county of San Francisco, State of California, have invented certain new and useful Improvements in Automatic Block-Signal Systems, of which the following is a specification.

This invention relates to an automatic block signal system which I have specially designed for use with an engine equipment consisting of devices respectively for both visible and audible signals and for automatically applying air brakes.

This invention more particularly relates to a combination of relays in which combination is included a time limit relay for controlling the circuits and for limiting the length of time that the track magnet is energized.

One of the objects of my invention is to insure accuracy of operation by the provision of safety devices to lock the various relays in their operative positions and to keep them so locked that the traffic conditions cannot interfere with their efficient operation.

Other objects will fully appear to those skilled in the art from the hereinafter description taken in connection with the accompanying drawings, in which the same reference characters indicate the same parts in the several views.

The engine equipment for use with this system is fully set forth in my co-pending application Serial No. 23,587, filed April 24th, 1915.

Referring to the drawings:

Figure 1 is shown on two sheets. The right half of this figure appearing on Sheet 1 and the left half appearing on Sheet 2. The entire figure showing two adjacent blocks with their respective circuit controlling devices.

Fig. 2. is a longitudinal vertical section of the time limit relay on staggered line 2-2 of Fig. 3.

Fig. 3. is a horizontal section of the time limit relay taken on staggered line 3-3 of Fig. 2.

Fig. 4 is a transverse vertical section of the time limit relay taken on line 4-4 of Fig. 2.

Fig. 5 is a horizontal section taken on line 5-5 of Fig. 2.

As is usual in railroad signal systems, the track is divided into a plurality of blocks, each block being insulated one from the other at suitable rail joints. Each block is provided at its respective ends with a battery connected to the rails and with a track relay also connected to the rails and in the center with an insulated section of track upon one side thereof. A circuit which is included in the track circuit is controlled by a protective relay and is shunted around the said insulated portion of track. The entrance of a train into either end of the block shunts out the track relay or the battery as the case may be and causes the armature of track relay to drop, thus opening the line contacts to set the necessary signals.

The circuits of two complete block signals are shown in Fig. 1 of the drawing, but only as controlling the operation of the track magnets which co-act with the automatic brake apparatus of the engine equipment. Circuits cooperating with the track magnets for controlling the various other signals such as the clear caution and stop signals operate in a similar manner and are omitted from the drawing for the purpose of simplicity and clearness.

Referring now to Fig. 1 contained on Sheets 1 and 2;

Block 1 is insulated from the adjacent block at one end by the insulating joints A and B and from block 2 by the insulating joints H and I and block 2 is insulated from its other adjacent block by the insulating joints U and V.

In each block at the signal location two more insulating joints are used, in block 1 at F and G and in block 2 at P and Q. These joints do not break the track circuits which are shunted around them by wires 1 and 2 through armature 3 of the protective relay 4.

As will be hereinafter explained, the disarrangement or failure of any of the location apparatus, batteries, wires, etc., will cause this protective relay to drop its armature, thus opening the track circuit and causing the display of the same signals as would be displayed if the block were occupied by a train. At the right end of block 1, a track battery D is connected to each side of the track by wires C and E near the insulations A and B, the current from the battery being

carried by the rails thence by wires 5 and 6 to a track relay J. In its normal position with no train in the block, this relay attracts its armature and connects the battery O by 5 means of line wires 7 and 8 to magnet 9 of the line relay in block 2. At the left end of block 2 is a track battery S connected to the rails by wires R and T near the insulating rail joints U and V, the current from the battery being carried by rails to the insulating joints H and I through the wires 10 and 11 to track relay K of block 2, the current being shunted around the insulated rail section between P and Q of block 2 through the circuit 10 controlled by the protective relay in block 2 as clearly shown.

In its normal position with no train in block 2, the relay K attracts its armature L and connects the battery M by means of 20 wires 12 and 13 with a magnet 9 of line relay of block number 1. It should be said for the sake of clearness that in actual practice, the blocks are not as closely connected as shown, the locations of the mechanisms 25 for operating the caution, stop and automatic stop signals allowing the engineer ample time to bring his train to a stop before the air is automatically applied. The space between the automatic stops controlling opposing train movements enables both trains to stop clear of each other if the brake has been automatically applied.

The mechanism for automatically operating the brake is placed far enough from the 35 danger zone to bring the train to a stop before it can enter that zone in the event that the engineer pays no heed to the warning signals.

In the event that two trains should enter 40 adjacent blocks at the same time, one entering at A and B and the other entering at U—V, then the batteries D and S which supply current for the relays J and K are shunted out by the wheels of the trains 45 bridging the rails, thereby causing the armatures N and L of these relays to drop, thus cutting out the batteries O and M from the magnets 9 of the line relays of blocks 1 and 2 thereby dropping the armature 14 and 50 its contact finger 15.

The character of the instruments, wiring, etc., are identical at both locations, therefore only one set will be described in detail as to operation. Reference is made for this purpose to Fig. 1. Line magnet 9 normally attracts and holds its armature 14 and the connected contact finger 15 clear of the contacts 16 and 17. As the line current is cut off, this armature is released and closes the 55 contacts 16 and 17. The armature 14 is connected through the wire 18 with one pole of a battery 19 and the current therefore travels through the wire 18, the armature 14, contact 16, wire 20 to the magnet 21 of the line relay thence through wire 22 to the

other pole of the battery 19 thereby energizing the magnet 21 and securely holding the finger 15 against its contact 17. The track magnet 23 is now set, that is to say, ready to be energized upon the closure of 70 contact 55, as hereinafter described, but no further movement of any part takes place until the forward truck of the engine passes insulating joint F. At the insulating joint G, a local battery 24 is connected to the 75 rails by wires 25 and 26. The current from this battery cannot enter the main track circuit as it is prevented from so doing by the insulating joints F and G, which joints, it may be here stated, are at a distance apart 80 of two rail lengths. At F the wires 27 and 28 connect the magnet 29 of the time limit relay and the current which is normally applied through the rails by the battery 24 causes this magnet to attract and hold up 85 the contact fingers 30 and 31, 32 and 33, thus holding open the contacts 34, 35, 36 and 37.

When the forward truck of the engine passes the insulating joint F, its wheels 90 bridge the rails and operate to shunt the magnet 29 out of circuit, and being thus deenergized, the contact fingers 30, 31, 32 and 33 are caused to drop. The contact finger 31 is connected by wires 38 and 39 with 95 one pole of the battery 19 and the current travels through these wires to wire 40 thence to magnet 41 thence through wire 42 to the other pole of the battery 19. The function of this magnet 41 is to lock the armature 100 contact fingers 32 and 33 securely against the contacts 35 and 37. As the contact fingers 32 and 33 drop, the current travels from the battery 19 through the wire 39 and contact 37 to the contact finger 33 thence to 105 contact finger 32 thence through the contact 35 and wire 43 to solenoid 44 thence through wire 45 to contact 46 thence through contact finger 47 and wires 48 and 22 to the other pole of the battery 19. To the core 49 of 110 the solenoid 44 is attached a frame 50 which is connected to pistons of two dash-pots 51 and 52. The frame 50 carries two projections 53 and 54. The function of the projection 53 is to normally depress the lever 115 55 and the function of the projection 54 is to lift the armature and contact fingers 47 and 56 attached thereto to a point near the magnet 57, which magnet is so designed that it will not attract the armature from the distance at which it normally rests. When the solenoid 44 is energized and the core drawn up, the projection releases the lever 55 and the projection 54 raises the armature carrying the contact fingers 47 and 56 into a 120 position at which the armature will be attracted and held in place by the magnet 57. As the core 49 reaches the end of its upward travel, the circuit of the solenoid 44 is broken by reason of the contact finger 47 125 130

being held disconnected from its contact point by the magnet 57. The circuit of said magnet 57 is controlled by a contact finger 30 which is connected to one pole of the 5 battery 19 by wires 38 and 39. The contact finger 30 co-acts with the contact 34 which is connected by a wire 58 to the magnet 57 and from said magnet 57 by means of wires 48 and 22 to the opposite pole of said 10 battery 19.

As above described, when the core 49 rises, the projection 53 allows the lever 55 to descend thereby closing the circuit to the track magnet 23 by means of the wire 59 from 15 battery 19 thence through said magnet 23 and wire 60 to the lever 55 thence by contact 61 and wire 62 to contact 17 thence by contact finger 15 and wire 18 to the other pole of the battery 19.

20 The dash-pots are so arranged that their retarding action takes place on the downward movement of the core 49 thus permitting the current to remain in the track magnet until such time as the projection 53 has 25 again depressed the lever 55 to open the circuit of the track magnet. The track magnet contacts cannot be set for another operation until the train has cleared the short rail section between insulating joints F, G, which 30 permit the current to again pass through the magnet 29 thereby attracting its armatures to break the circuit of the magnet 57, permitting contact fingers 47 and 56 to return to their normal position.

35 The function of the protective relay 4 is as follows:—

With the line and time limit relays in their normal positions, the relay 4 is connected across the open circuit between the 40 lever 55 and the contact 61 by means of the wire 63 to contact finger 56 thence by contact 64 and wire 65 to relay 4 thence by wire 66 to contact 61. The lever 55 is connected by wire 60 to track magnet 23 thence 45 by wire 59 to one pole of the battery 19. Its circuit is completed by wire 66 to wire 62 thence to a high resistance 67 (bridged across the terminals of armature 14 and wire 62) thence by wire 18 to the other pole of 50 the battery.

The relay 4 is of high resistance and the resistance connected in series with it at 67 reduces its operating current to an amount just sufficient to enable it to securely retain 55 its armature 3. Any diminution of voltage of the battery 19 below its normal operating point, will cause the magnet 4 to weaken, thus dropping the armature 3 and opening the track circuit by means of the wires 1 60 and 2 and thus set the proper danger signals the same as if the block were occupied by a train. The breaking of any wire in the external circuit will also produce the same result. Should the local battery 24 65 or its connections 25 and 26 fail or should

the wires 27 or 28 leading to the magnet 29 be broken thus causing the plunger 49 to be operated, then the relay 4 will be cut out by the opening of the contact between contact finger 56 and contact 64. The opening 70 of these contacts in the ordinary course of delivering a signal, produces no effect as the track circuit has already been shunted by the entrance of a train into the block. 75 68 and 69 indicate condensers which are connected across the contacts shown to dissipate the inductive spark occurring on breaking the circuit. Auxiliary carbon contacts (not shown) are also provided between the lever 80 55 and contact 61 to further protect the contacts against sparking.

The time limit relay referred to in the foregoing description will now be described in detail, reference being made to Figs. 2, 3, 4 and 5.

85 The time limit relay comprises a top plate 70 to which the various magnets are secured; a mid-plate 71 secured by pillars 72 to the top plate and a bottom plate 73 connected in any suitable manner to the top plate 70, 90 the sides of the casing consisting of glass plates secured in any suitable way between the top and bottom plates. The electromagnet 29 is secured to the top plate 70 and is provided with an L-shaped pole piece 95 29^a, the horizontal portion of which co-acts with the armature 29^c. This armature is pivoted at 29^d and carries the contact fingers 32 and 33. The locking magnet 41 is secured to the top plate by brackets 41^a 100 and is provided with extended pole pieces 41^b which underlie the armature 29^c and are adapted to co-act with said armature.

The portions 29^b of the pole piece of the magnet 29 are adapted to co-act with the 105 armature 29^c. This armature is pivoted at 29^e and carries contact fingers 30 and 31. These fingers are normally out of contact with their respective contact points 34 and 36 and the same thing is true of the fingers 110 32 and 33 with respect to the contact points 35 and 37.

When a train enters the insulated rail section, it shunts out the circuit which normally flows through magnet 29 thus allowing 115 the armatures 29^c and 29^e to drop. This completes the circuits as set forth in the foregoing description of the system and energizes magnet 41 which securely holds the armature 29^c and its contact fingers in 120 their operative position. The solenoid 44 is provided with a double core 49 to which is secured a frame 50 comprising a top cross bar 50^a secured to each core and a bottom cross bar 50^b secured together by spacing 125 rods 50^c.

Secured to the bottom cross bar 50^b are the piston rods 51^a and 52^a of the pistons 51^b and 52^b. These pistons operate in the dash-pots 51 and 52 respectively in such 130

manner that they afford very little break during the upward movement when the solenoid is energized, the ball check valves 51^a and 52^a allowing the air to escape freely. Conversely when the solenoids are deenergized and gravity causes the frame to descend, the dash-pots operate as a timing device to govern the rate of travel. A threaded rod 50^a having a head 50^c is secured to the bottom cross bar 50^b and is provided with a jam nut 50^e by means of which it may be firmly held in any predetermined position. 55 is a rectangular lever frame pivoted at 55^a to bars secured in the mid-plate 71. This frame is provided at one end with the contact fingers 55^b and at the opposite end with an extension piece 55^c having an aperture therein through which the rod 50^a passes.

10 The solenoid 44 is normally deenergized and therefore the frame is in the position shown with the head 50^c of rod 50^a in engagement with the extension piece 55^c of the pivoted frame 55 thereby holding the contact fingers 55^b out of engagement with the contacts 61.

20 Secured to the cross bar 50^a is a post 54^a which extends downwardly therefrom and to the lower face of which is secured a projecting finger 54.

25 The armature 57^a is pivoted at 57^b and is normally out of range of the effective magnetic field of magnet 57 and its contact fingers 47 and 56 are normally in engagement with their respective contacts. When the solenoid 44 is energized, the cores 49 move upwardly and after a short interval of time, the projecting finger 54 engages a block of insulation 57^c secured to the armature 57^a.

30 As the finger 54 continues its upward travel, it rocks the armature 57^a on its pivot 57^b causing its contact fingers 47 and 56 to move out of engagement with their contacts and at the same time bringing the armature 57^a into the effective field of the magnetic flux so that said armature is held up as long as there is sufficient current flowing through magnet 57.

35 The condenser 69 is supported between the mid-plate 71 and a similar plate 71^a secured to the pillars 72.

40 The condenser 68 is secured by cross bars 74 and 74^a which are secured to the pillars 72^a.

45 *55 Functions of the various relays used in this system.*

Track relay.

50 One of these instruments is used at the end of every block and supplied with current through the rails by a battery at the other end of the block. In its normal, or clear position, its armature is held up and, 55 while in that position, holds all signals clear

on the lines to which it is connected. When the relay is shunted or cut out by the presence of a train in the block, its armature drops away and, while in that position, gives the necessary caution and danger signals on the lines to which it is connected.

Line relay.

These instruments are used at every signal location, the number required depending on the character of the signals to be given at that particular location. For a location displaying a clear and caution signal, one line relay is required, operating the clear signal in its normal or closed position and operating the caution signal in its open position. For locations displaying a danger signal or operating an automatic stop, one line relay is required for each operation; these give no signal in their normal or closed positions, but only display a signal or operate the automatic stop when in the open position. Line relays are connected, through necessary battery and line wires, to the front contacts of track relays, *i. e.*, the contacts which are normally closed. The opening and closing of these contacts, as above described, effects a corresponding operation of the line relays.

Time limit relays.

One of these instruments is used at every signal and stop location, only one being required regardless of the number or character of the signals displayed at that particular location. This relay cuts the track magnet into circuit as the engine reaches a point two rail lengths from the signal location, holds said track magnet in circuit for a period of approximately twelve to fifteen seconds and then cuts it out of circuit. If any portion of the train is still passing over the insulated rail section of the signal location after the lapse of fifteen seconds or if a car is left, for any reason, over the insulated rail section, the relay will still hold the magnet box circuit open and will not return to its normal position until the train or car has cleared the insulated rail section. As the insulated rail section at locations is clear of the rest of the block, the relay is arranged to give a warning signal on adjacent blocks in case a car or light engine is left standing in the insulated rail section. Another feature is the giving warning by the operation of the relay itself in case the local battery or any of the external wiring to track connections fail from any cause.

The operation of my above described system is briefly as follows:—

When a train equipped as described in my application Serial No. 23,587, filed April 24th, 1915, enters a block before the train ahead clears itself from the adjacent (or some other selected) block, the track relays

of the respective blocks are deenergized causing the line relays to operate to set the track magnet, which is situated adjacent an insulated section of track. When the track

5 magnet is in this condition and the train enters the insulated section before the train ahead is clear of its block, the time limit relay is operated and causes the track magnet to be energized, and remains in that 10 condition for a length of time sufficient to cause the signals or the automatic brake to operate upon the train which is moving at a minimum rate of speed. The time for which the magnet is energized is made variable by adjusting the size and construction 15 of the dash-pots and pistons.

By setting the relay to cut out ten seconds after it has been started it may be used to enforce a definite speed reduction to enable 20 an engineer to run past an automatic stop location. For instance—with the local track circuit at each location two rail lengths, or 66 ft. long, it will take an engine twelve seconds to travel that distance when 25 going at the rate of four miles an hour; therefore, the track magnet will have been cut out before the engine passes over it thus preventing the application of the brakes. It will not, however, prevent the resuming 30 of a higher speed once the automatic stop has been passed.

The relay prevents waste of battery by preventing the track magnet from being kept in circuit for a longer period than 35 fifteen seconds which is ample time to deliver a signal to the slowest train, the lock-out magnets, which accomplish this purpose, are of relatively high resistance and require little current for their operation.

40 While the above described relay forms a positive and efficient instrument, it is to be understood that details of construction may be changed without departing from the spirit and scope of my invention.

45 As many changes could be made in the above construction and many apparently widely different embodiments of the invention could be made without departing from the scope thereof, I intend that all matter 50 contained in the above description or shown in the accompanying drawings shall be interpreted as illustrative and not in a limiting sense.

I desire it also to be understood that the 55 language used in the following claims is intended to cover all of the generic and specific features of the invention herein described and all statements of the scope of the invention, which, as a matter of language, might be said to fall therebetween.

Having now described my invention, what I claim as new and desire to secure by Letters Patent is:—

1. In a device of the kind described, a 60 time limit relay including two magnets, a

track magnet, a separate circuit for each magnet, a single source of electrical energy common to the track magnet and one of the relay magnets, means for energizing one magnet of the relay when the other magnet is deenergized. 70

2. In a device of the kind described, a time limit relay including two magnets, a track magnet, each magnet in separate circuits, a source of electrical energy common 75 to the track magnet circuit and to the circuit of one of the relay magnets, and means for energizing one magnet of the relay when the other magnet is deenergized to hold the circuit of the track magnet in condition to 80 be subsequently closed.

3. In a device of the kind described, a time limit relay including two magnets, a track magnet, each magnet in separate circuits, a source of electrical energy common 85 to the track magnet circuit and to the circuit of one of the relay magnets, means for energizing one magnet of the relay when the other magnet is deenergized to hold the circuit of the track magnet in condition to 90 be subsequently closed, and means for closing said circuit.

4. In a device of the class described, an insulated section of track, a time limit relay, a track magnet, a magnet controlling the 95 said time limit relay in circuit with said insulated section of track, means operated with the time limit relay normally holding the circuit of the track magnet open, and means for energizing the track magnet, said 100 means being controlled in its operation by the time limit relay.

5. In a device of the class specified, an insulated section of track, a time limit relay and a track magnet, a protective relay controlling a circuit shunted around said section, means for energizing said protective relay included in circuit with the time limit relay and the track magnet, and means for deenergizing said protective relay upon the 105 breaking or failure of action of any portion of the controlling circuit. 110

6. In an automatic block signal system, a solenoid, a plurality of electro-magnets controlling the operation of the solenoid, a 115 source of electrical energy, a track magnet, and means controlled by the solenoid for controlling the circuit of said track magnet.

7. In an automatic block signal system, a track magnet, an electric circuit therefor, a 120 solenoid, an electric circuit therefor, a source of electrical energy common to the two circuits, an electro-magnet in circuit with said source of electrical energy for locking closed the circuit of the solenoid, 125 and means operated by the solenoid for completing the circuit of the track magnet and for breaking the circuit of the solenoid.

8. In an automatic block signal system, an insulated section of track, a track mag- 130

net, a plurality of electro-magnets, one of said magnets being in circuit with the insulated section of track, contact fingers controlled by said magnet, another magnet the circuit of which is controlled by said contact fingers, another set of contact fingers controlled by said first mentioned magnet, a locking magnet for said second set of contact fingers, a source of electrical energy in circuit with said locking magnet, a solenoid the circuit of which is controlled by the said second set of contact fingers when in their locked position, means operated by the solenoid for controlling the circuit of said track magnet, and means also controlled by the solenoid for breaking its own circuit.

9. In an automatic block signal system, a

circuit normally open at one point, a source of electrical energy, a relay in said circuit and a resistance across said open point.

10. In an automatic block signal system, a circuit normally open at a plurality of points, a source of electrical energy, a relay connected across one of said points, and a resistance connected across another of said points.

In witness whereof I have hereunto set my hand at the city and county of San Francisco, State of California, this 21st day of June, 1915.

WALTER S. LEVIN.

In presence of—
S. A. BOSTWICK,
H. R. BOSTWICK.
